UNITED STATES PATENT OFFICE.

HARRY P. NISSEN, OF OAKLAND, CALIFORNIA.

FASTENER FOR SLEEVE HOLDERS.

Application filed November 3, 1925. Serial No. 66,445.

This invention relates to sleeve holders and particularly pertains to a sleeve holding device for use in yieldably retaining the cuff of the sleeve in any desired position on 5 the arm.

It is the principal object of the present invention to provide an improved fastener for sleeve holding devices which are used in combination with the snap type of cuff links, 10 which devices may be disposed concealed within the cuffs when the cuffs are in use and will cause the cuffs to yieldably grip the arms at any position thereon when the cuffs are folded back on the sleeves.

15 In carrying out this object I provide an elastic member having hook means at opposite ends for detachably connecting it to the opposite halves of the snap type for cuff link. When the cuff is in use, the device is 20 concealed within the cuff and the hooks do not interfere with the operation of the links. When the cuff is opened and folded back upon itself, the elastic member is placed under tension so that the cuff will yieldably 25 grip the arm to hold the sleeve in any desired position thereon. In this manner the cuff may be raised and retained above the elbow without rolling the sleeve which results in wrinkling the cuff.

30 One form which the invention may assume is exemplified in the following description and illustrated by way of example in the accompanying drawings, in which:

Fig. 1 is a view of a portion of a shirt 35 sleeve and arm disclosing the cuff folded back with my improved device applied to the cuff links.

Fig. 2 is a view looking into the end of the cuff disclosing the manner in which my 40 device is concealed within the cuff when the latter is in use.

Fig. 3 is an enlarged view of the novel type of hook employed for detachably connecting the device with the cuff links.

45 Referring more particularly to the accompanying drawings, 10 indicates a shirt sleeve on an arm 11. The shirt sleeve is formed with a cuff 12 which in Fig. 1 is shown as folded back upon itself. It is impossible whether or not the cuff is of double or single type. The cuff and shirt sleeve are split as at 14 and the contiguous sides of the cuff are formed with button holes 15 for receiving cuff links.

50 The present invention is particularly applicable for use in connection with the snap

type of cuff links which comprises two halves having a male and female means for frictionally connecting them. Each half of the cuff link comprises a pair of spaced collars 16 joined by a shank 17 which is of smaller diameter than the collars. Connected to these halves of the link is a sleeve holding device 18 with which the present application is particularly concerned. This 60 device comprises a strip of elastic material 19 which is formed with loops at its opposite ends. These loops detachably connect with hook members 20 which are adapted to detachably engage with the opposite halves 65 of the cuff link. These hooks are adapted to engage the shanks 17 of the opposite halves of the cuff links so that they will be interposed between the inner collars 16 on the link and the cuff. 70

When the cuff is disposed in normal position with the cuff link halves connected, the elastic portion 19 of the device will be concealed within the cuff as disclosed in 75 Fig. 2.

When it is desired to raise the cuff on the arm for any reason, the cuff link halves are disconnected and the cuff is folded back on the sleeve as disclosed in Fig. 1. This may be accomplished without disengaging the 80 sleeve holding device 18 from the opposite halves of the cuff links.

In folding the cuff over the shirt sleeve, the elastic portion 19 of the device 18 will be placed under tension so that the cuff will 85 yieldably grip the arm. The cuffed end of the sleeve may then be drawn upwardly on the arm to any desired point, the elasticity of the portion 19 of the sleeve holder accommodating the different portions of the 90 arm encountered. Regardless of the position of the cuff on the arm, the elastic portion 19, being under tension, will cause the cuff to yieldably grip the arm and maintain the sleeve in position. This is very desirable as 95 it renders rolling of the sleeve unnecessary. Likewise the hooks 20 of the sleeve holding device 18 prevent the cuff link halves from becoming detached from the cuff and being 100 lost.

I desire to call attention to the novel construction of the hook 20. Referring to Fig. 3 wherein one of the hooks 20 is illustrated in detail, it is seen that the hook is formed of a single length of spring steel wire. The 105 ends of the wire are disposed parallel and terminate adjacent the longitudinal center 110

of the hook. From this point the wires extend outwardly, thence longitudinally a short distance after which they are bent back upon themselves to form transverse portions 22 and 22^a. The transverse portion 22 is looped about the longitudinal center of the hook to form an inner ring 23. This ring is not a complete circle but terminates short of the transverse portion 22, and is then bent 10 back upon itself to form an outer ring 24.

The point where the inner ring 23 is bent back upon itself constitutes the tip 25 of the hook, which, as described, is located at a spaced distance from the transverse portion 15 22 so that a throat 26 will be formed. It is also apparent from Fig. 3 that the outer ring 24 is spaced a distance from the inner ring 23. This outer ring is formed somewhat eccentric relative to the inner ring 23 20 so that one portion of the outer ring will be closely adjacent to that portion of the inner ring 23 opposite the throat 26. At this point a rigid connection 27 is formed between the rings and the outer ring 24 is then 25 continued into the transverse portion 22^a. As the transverse bars 21 or the ends of the wire are not connected, by pressing inwardly against the sides of the hook, as indicated by the arrows A—A, the transverse portion 30 22 and its bar 21 will move inwardly and will enlarge the throat 26. In other words, the transverse portion 22 pivots at the point where the inner ring is rigidly connected to the outer ring and will move away from the 35 hook tip 25. This tip will remain stationary relative to the remaining portion of the hook due to the rigid connection 27 between the inner and outer rings.

40 Although the inner ring 23 constitutes the engaging element for engaging the shank 17 of the cuff link halves, the outer ring 24 serves the function of a guard for prevent-

ing the inner ring from passing through the button hole and retains the cuff link half in proper position.

45 It is also desired to point out that due to the separating bars 21, the hook may be easily engaged with the elastic portion 19. The hook disclosed in the present instance is adapted for purposes other than in connection with the particular form of device here disclosed.

50 While I have shown the preferred form of my invention, it is to be understood that various changes in its construction may be made without departing from the spirit of the invention as defined in the appended claim.

55 Having thus described my invention, what I claim and desire to secure by Letters Patent is:

56 In a device of the character described, a hook formed of a single length of wire, the ends of which overlap and extend in parallelism outwardly in opposite directions to 60 form a divided bar for engaging a loop, longitudinal portions at the outer ends of the bar, transverse portions formed as continuations of said longitudinal portions and extending inwardly, one of said transverse 65 portions terminating in an inner ring, the other transverse portion terminating in an outer ring, contiguous ends of said rings 70 forming a tip disposed short of the transverse portion terminating in the inner ring whereby a throat may be formed, a rigid connection between the rings at a point diametrically opposite the throat, the transverse portion which terminates in an inner ring being yieldable whereby the throat may be 75 enlarged if desired by pressing inwardly against both outer ends of the divided bar simultaneously.

80 HARRY P. NISSEN.
